(57) CLAIM

The ornamental design for a vehicle tail light, as shown and described.

DESCRIPTION

FIG. 1 is a front elevational view of the tail light, with its light emitting diode array lit; and,

FIG. 2 is a perspective view of the tail light with its light emitting diode array unlit, and showing its encasement box.

The tail light's encasement box is not part of the claimed design and not part of the design sought to be patented.
